TELESCOPE MOUNTING

Joseph M. Moore, Bremerton, Wash.

Application March 2, 1951, Serial No. 213,540

2 Claims. (Cl. 33—50)

1

This invention relates to improvements in mountings for telescopes as used with the ordinary types of hunting and army rifles for sighting purposes, and it is the principal object of the invention to provide simple and practical mounting means for the secure and functional support of a telescope in sighting position on a rifle, and which permits the telescope to be easily and quickly applied to the rifle and likewise to be easily and readily removed when its use is not required.

It is a further object of my invention to provide a telescope mounting means including coacting parts that are secured to the gun and to the telescope respectively, and are adapted to be interengaged in holding contact and then to be locked in such relationship by the hand turning of a clamping and securing cam lock; the reverse turning of the cam effecting release and making it possible to remove the telescope from the mountings.

Further objects and advantages of the invention reside in the details of construction, of the various parts; and in their combination, coaction and mode of use, as will hereinafter be fully described.

In accomplishing these and other objects of the invention, I have provided the improved details of construction, the preferred forms of which are illustrated in the accompanying drawings, wherein—

Fig. 1 is a side view of a portion of a rifle on which a telescope is functionally mounted by means embodied by the present invention.

Fig. 2 is a similar view, showing the relative disposition of the telescope for its application to the rifle.

Fig. 3 is a cross-sectional detail of the rearward mounting for the telescope.

Fig. 4 is a vertical section of the telescope mounting means taken in a plane that extends longitudinally of the rifle.

Fig. 5 is a cross-section on line 5—5 in Fig. 4.

Fig. 6 is a cross-section on line 6—6 in Fig. 4.

Fig. 7 is a cross-section on line 7—7 in Fig. 4.

Fig. 8 is a perspective view of the coacting parts of the mounting as provided for support of the forward end of the telescope.

Fig. 9 is a perspective view of coacting parts comprised in the mounting means as provided for support of the rearward end of the telescope.

Fig. 10 is a cross-sectional detail of the rear end mounting as applied to the telescope.

Referring more in detail to the drawings—

It is not the intent that the present telescope

2

mounting means be confined to any particular make of gun or rifle, or that it shall apply to any particular make of telescope. Therefore, it is to be considered that the gun or rifle, and the telescope herein shown, are typical of those to which the present mounting means are applied and that such changes as may be required to adapt them to different makes of rifles or telescopes may be made.

10 In Figs. 1 and 2, 10 designates a portion of the stock and 11 a part of the rifle barrel secured thereto, and 12 designates a common type of telescope used with such rifles. Formed as a part of the breach end of the barrel, or as a separate part secured thereto, is a metal plate 13 upon which the telescope is adapted to be removably secured by the means embodied by this invention.

15 Fixed to the plate 13, on the top side and at the forward end thereof, is a block 16 which, as shown best in Fig. 8, comprises a flat, plate-like body portion 16x disposed lengthwise of the plate 13 and secured rigidly thereupon by two screws 17, applied through the block and into plate 13. Formed as an integral part of plate 16x, along opposite sides thereof, are upstanding wings 18—18, with parallel inside surfaces. The rearward end surface of the plate 16x is formed with an undercut beveled surface, as clearly shown at 16a in Fig. 8. The body block 16, comprises the base member of the forward end mounting means for the telescope.

20 Mounted on the plate 13, at its rearward end, and in a manner presently explained, is a mounting block 20 for the rearward end of the telescope. This block, as shown best in Fig. 9, is formed at opposite sides with upstanding wings 21—21 with parallel vertical inside surfaces.

25 Applied to the telescope barrel, near its forward and rearward ends respectively are mountings, designated generally in Figs. 1 and 2, by numerals 25 and 26. These mountings are arranged to coact with the forward and rearward mounting blocks 16 and 20, respectively, for the functional securing of the telescope to the gun.

30 The forward end mounting 25, as well shown in Figs. 6 and 8, comprises a base block 25x, formed with an upwardly facing cylindrically curved seat 25s, corresponding to the cylindrical curvature of the telescope barrel, and in which the latter is seated. A strap 27 is applied over the telescope barrel and is secured at its ends to the opposite side surfaces of the block 25x, as seen 35 in Figs. 1, 2 and 6, by means of screws 28.

Formed along the under side of block 25x as an integral part thereof, is a longitudinal rib or key 25y, with parallel and vertical opposite side surfaces. This rib is designed to be snugly received between the wings 18-18 formed on the block 16 for the securement of the forward end of the telescope. At its rear end and under side, the rib 25y has a transversely directed stop shoulder 30 extending downwardly therefrom, and this shoulder has a downwardly and forwardly beveled forward surface 30' adapted to engage in interlocking relationship with the undercut beveled surface 16a of the end plate 16x, as has been clearly shown in Fig. 4.

As a feature of construction designed to facilitate the application of the telescope to the forward mounting block 16, the under surface of the longitudinal rib 25y is upwardly and forwardly inclined from the shoulder 30 as best understood by reference to the relationship of the coacting parts as shown in Fig. 4. This is to permit an easy application of the rib 25y to the channel provided between the wings 18-18 on block 16, and the engaging of shoulder 30 with the undercut beveled end of plate 16x while the rear end of the telescope is disposed substantially in the inclined and easy handling position of Fig. 2. After engaging the coacting forward end mountings, as applied to the gun and telescope, the rear end of the telescope is then swung downwardly to engage the coacting rear end mountings.

The rear end mounting, as applied to the telescope, comprises a base block 26x formed with a cylindrically curved top surface 26y, as seen in Figs. 5 and 9, in which the telescope barrel is seated, and a strap 26s is applied over the telescope with its opposite ends secured to the opposite side faces of the block by screws 35. This mounting is closely fitted to the telescope but permits slight longitudinal adjustments thereon, for a purpose presently explained. To hold the mounting against movement on the telescope after being set at a desired position of adjustment, I have mounted a friction block 38 of a suitable material such as wood, in the telescope seating surface of the base block 26x. This friction block is contained in a pocket 40 in block 26x as shown in Fig. 10 with its inner surface curved to fit the surface of the telescope barrel. A set screw 42 is threaded through strip 26s of block 26x against the outer end of block 38 and is adjustable inwardly to force block 38 into tight holding contact with the telescope thus to fix the mounting 26 in a definite spaced relationship to mounting 25.

The base block 20 is formed across its forward end, as seen in Fig. 4, with a transverse and rearwardly sloping surface 44. This surface of block 20 coacts with a locking cam carried by the mounting 26 to lock the telescope in functional position on the gun.

It is shown in Fig. 5 that the base block 26x is formed on its under side with an integral, longitudinally extending rib 50 adapted to be snugly received between the spaced wings 21-21 of the block 20. Depending from the forward end of the rib, in spaced relationship, are ears 52-52 between which a locking cam 53 is located. This cam is fixed on a cross shaft 54 revolvably mounted in the ears. On one end of the cross shaft is an operating lever 55 by means of which the cam can be rotated and brought into and from holding contact with the beveled surface 44 of block 20, as shown in Fig. 4. When so locked, the lever

55 will rest flatly against plate 13 as shown in Fig. 4.

The cam 53 is so designed that when in locking position, its contact point with surface 44 is slightly over dead center position and thus there is no likelihood of its becoming accidentally released. By swinging the lever upwardly from the position of Fig. 4, the cam will clear the beveled surface 44 and the telescope can be 10 lifted upwardly at that end.

In order to positively hold the mounting 26 at an exact and definite spacing from the mounting 25 and to prevent any slippage that would nullify the holding effect of the cam 53, I have 15 mounted a spacer rod 60 between the mountings 25 and 26 as best shown in Fig. 4. This rod has its forward end threaded into a bore 62 in block 25x and has its rearward end conically tapered and seated in a socket 63 in block 26x. To properly set the mountings on the telescope, pressure of the friction block 38 is released and the rod 60 is adjusted endwise away from the block 26x. Then the telescope is applied to the gun as shown in Fig. 4. Before the cam 53 is turned to locking position, the rod 60 is extended to seat its rearward end in block socket 63 and shift the rearward mounting to position as shown in Fig. 4. Then the lock nut 70 on rod 60 is tightened against the rear end of rib 25y to secure the adjustment of rod 60. The friction block 38 is then set inwardly by set screw 42 to hold the mounting against any shifting away from the forward mounting under the impact of or influence of "kick" of the gun in use and the cam 53 is turned to locking position.

The block 20 which mounts the rear end of the telescope is fixedly mounted on the plate 13 by screws 20s. At one side of its rearward end portion, the block has a laterally and downwardly extending leg 74 as shown in Figs. 3, 5 and 9. Across this rear end portion of the block a flat plate 72 is secured by a screw 73 through one end portion and into the leg 74. The plate 72 is formed with a slot 74, transversely of the line of the telescope, and movably mounted therein is a peep sight block 75. At one end the plate 72 has an upturned flange 76. An adjusting screw 77 extends through this and is threaded through the sight block for its lateral adjustment as may be required. This remains in position of use when the telescope is moved.

With the gun so equipped with the mountings 16 and 20, and the telescope equipped with the mountings 25 and 26, the telescope can be easily 55 and readily applied merely by first engaging the forward mounting 25 with mounting 16 as shown in Fig. 2, then swinging the rear end of the telescope downwardly to seat the mounting 26 in mounting 20 and then securing the locking cam by use of lever 55. Releasing action of the cam by upward swing of lever 55 permits the telescope to be removed from the gun.

The application of the mountings 16 and 20 in no way interferes with the normal sighting 65 of the gun when the telescope is removed therefrom.

Having thus described my invention, what I claim as new therein and desire to secure by Letters Patent, is:

1. A telescope mounting means comprising front and rear blocks adapted to be secured to a gun in fixed spacing along the gun barrel, said blocks each having laterally spaced wings uprightly standing therefrom and lengthwise of the barrel, and having adjacent end surfaces formed by an

undercut bevel; mountings adapted to be applied to a telescope barrel, lengthwise thereof and in a spaced relationship corresponding to the spacing of the blocks; each mounting having a rib formed thereon lengthwise of the telescope, said ribs being adapted to be snugly received between the wings of corresponding blocks to establish the functional alignment of the telescope with the gun barrel; one of said ribs having a depending shoulder formed across its inner end and having its under surface sloping therefrom toward the telescope, thus permitting the shoulder to be hingedly engaged with the beveled end surface of the corresponding block before the rib of the other mounting has been 15 disposed between the wings of the other block, and means on the said other mounting to engage in clamping contact with the beveled end surface of said other block after both ribs have been received between the wings of the blocks.

2. A telescope mounting means comprising a plate adapted to be fixedly secured to a gun barrel lengthwise thereof, blocks formed integral with the plate upon its opposite ends, each block having laterally spaced, upstanding wings 25 formed thereon in the longitudinal direction of the plate, and the adjacent end surfaces of said blocks being undercut bevels, collar type mount-

ings adapted to be applied about a telescope, and formed on their under sides with ribs adapted to be received between the wings of corresponding blocks to establish the alignment of the telescope with the gun, clamping means on the mountings for engaging the beveled end surfaces of the blocks, means for actuating one of the clamping means from and into clamping engagement with the beveled end surface of the corresponding block, and a rod extended between the mountings and a nut adjustable thereon against one of the mountings to establish their spaced relationship.

JOSEPH M. MOORE.
